G. B. WHEELER,

WASHBOARD.

APPLICATION FILED SEPT. 11, 1920

1,394,801.

Patented Oct. 25, 1921.

UNITED STATES PATENT OFFICE.

GEORGE BERNARD WHEELER, OF NEW YORK, N. Y.

WASHBOARD.

1,394,801.

Specification of Letters Patent. Patented Oct. 25, 1921.

Application filed September 11, 1920. Serial No. 409,704.

To all whom it may concern:

Be it known that I, GEORGE BERNARD WHEELER, a citizen of the United States, and a resident of the city of New York, borough 5 of Manhattan, in the county and State of New York, have invented a new and Improved Washboard, of which the following is a full, clear, and exact description.

This invention relates to washboards, and 10 has for an object the provision of an improved arrangement whereby apparel and the like may be washed and thoroughly cleansed with little labor, and without injury to the material.

15 Another object in view is to provide a washboard with a grooved roller rubbing face.

A further object in view is to provide a washboard with removable extension legs, 20 whereby the length of the board may be varied to suit any washtub.

A still further object in view is to provide a washboard with an arm, or resting rail mounted above the frame, that will yield, 25 with weight or pressure upon it.

In the accompanying drawings:—

Figure 1 is a front elevation of a washboard embodying the invention;

Fig. 2 is a side elevation, wherein the 30 sliding plate is shown to full view;

Fig. 3 a rear elevation;

Fig. 4 a section on line 4—4 of Fig. 1;

Fig. 5 is a transverse section of one of the grooved rollers on line 5—5 of Fig. 4;

35 Fig. 6 is a fragmentary section on line 6—6 of Fig. 1;

Fig. 7 is a fragmentary section of a slight modification of the invention to that shown in Fig. 8;

40 Fig. 8 is a fragmentary view of the bearing strip fixed in the groove of one of the side pieces.

Referring to the accompanying drawing by numerals, 1 and 2 indicate the sides of a

45 frame which may be of hard wood having a smooth grain, the upper ends of which are dove-tailed and engage grooves at the ends of cross-piece 3. Side pieces 1 and 2 are also braced with a cross-piece 4 which is doweled 50 at both ends, and engages apertures through 1 and 2. Cross-piece 4 is provided with cross-cut grooves 5, and of which there may

be any desirable number, to prevent soap from slipping from one side to the other and also to allow water to drain off the 55 cross-piece which also forms part of the soap-pocket 6, which is intended to be deep. The back 7 more particularly shown in Fig. 3, may also be provided with grooves 8, as shown in Fig. 4, so as to provide a further 60

means of preventing soap from slipping into the washtub and to allow water to drain off. Back 7 also acts in another capacity hereinafter fully described. 9 is the lower cross-piece of the frame, and engages side-pieces 1 and 2 in a like manner to cross-piece 4. Cross-pieces 3, 4 and 9 forming part of the frame are rigidly secured to the side-pieces 1 and 2 by screws 10, or by other means. 11 are the rollers, and of which 70

there may be any desirable number, but ten are preferred, and may be of hard wood having a smooth grain, and are provided with any desirable number of V or U shaped grooves 25 running parallel from end to 75 end, more particularly shown in Fig. 5. A bearing pin 12 shown in Fig. 4, is rigidly fastened at one end of each roller by being driven into the wood up to the shoulder 13 of the bearing pin. The opposite end of the 80

roller is provided with a bearing pin 14, shown in Fig. 4, and more particularly in Figs. 5 and 6, which extends through a metallic sleeve 15 having an aperture 16. The bearing pin is provided with a flat head 17 85

which bears against spiral spring 18, which is loosely positioned in a socket in the end of the roller, in which the metallic sleeve is rigidly held. The shoulder 19 of the sleeve rests upon the surface of the roller, while 90

the flat head 17 of bearing pin 14, is held against the inner rim of the sleeve and the pin cannot slip out of the sleeve, but is always extended. Pin 14 which acts as a shaft engages an aperture 20 in bearing strip 95 21, shown in Figs. 2 and 8. The bearing strip may be of zinc, brass or other rust-proof metal, and may be provided with any desirable number of apertures 20, and of a desirable length, width and thickness to engage groove 22 in side piece 1 of the frame, and be rigidly secured thereto by screws or other means, the bearing strip being provided with apertures 23 and 24 through

which the screws may pass and be screwed into the wood. Side piece 2 is also provided with a bearing strip 21 in a like manner to side piece 1, so that bearing pin 12 may engage a corresponding aperture 20 and the roller be held in the frame, and the roller may revolve with freedom. 26 indicates apertures in side piece 1, and if desired side piece 2 may be provided with apertures 26, 10 the apertures in side piece 1 providing a means whereby one or more rollers 11 may be removed without difficulty should they become broken or out of order, to replace them with new rollers, by simply inserting 15 a wire nail or any other desirable instrument in the aperture and forcing the bearing pin back into the roller and lifting the roller from the frame, and substituting new rollers. Side pieces 1 and 2 are also provided with apertures 27, shown in Figs. 1, 2, 7 and 8 so as to engage pins 28 and 29 of extension legs 30. The pins may be in the form of screw-bolts and arranged as I may elect, or rigidly fixed to the legs, which may 25 be of wood or other material. An aperture 31 is also provided in the legs, and through which screw-bolts each having an engaging metallic washer passes, thence through one of the apertures 27 through the lower ends 30 of side pieces 1 and 2, and the extension legs may be rigidly secured to the lower ends of the side pieces by the screw-bolts each having an engaging washer and a thumb-nut. Thus, the length of the board may be varied 35 to suit any washtub, or the extension legs may be removed and discarded if desired, and without injury to the structure. In Figs. 1, 2 and 3 are shown the resting arm or rail, which is intended to provide a means 40 whereby a woman in washing upon the board may rest, and shock may be absorbed. The rail 32 which may be of wood or other material, yields when weight or pressure is placed upon it, being provided with spiral 45 springs 33 and of which there may be one or more. The spiral springs 33 are loosely held in position by setting into sockets in cross-piece 3, and in a like manner in rail 32. A movable or sliding plate 34, which may be 50 of any desirable and pliable metal, and formed with a longitudinal slot 35 therethrough, as shown in Fig. 2, and two or more apertures 36 at the top or upper end of the plate, is rigidly fastened to one end of 55 rail 32 by screws passing through apertures 36 and screwed into the wood, and two or more screws having round heads and engaging washers, passing through slot 35 and screwed into side-piece 1, the opposite end 60 of the rail being provided with a sliding plate in a like manner. In Fig. 3, is shown the backboard 7 which may consist of any desirable number of slats, boards or strips, and which may be of wood or other material 65 and arranged across the frame from side-

piece 1 to side-piece 2 and secured thereto by screws or nails 37, and providing a means whereby apparel and the like in a washtub will not interfere with the action of the rollers, and also to allow the soiled water 70 to drain off into the bottom of the tub, and to strengthen the structure.

In Fig. 7 will be seen a modified form of the invention in which the bearing strip 50 is stamped and formed of sheet spring metal, 75 brass preferred, and having apertures 20, 23 and 24, apertures 20 acting as bearings for bearing pins, hereinbefore described. The bearing strip it will be observed engages groove 22 in the side-piece, to which 80 it is secured by screws passing through apertures 23 and 24 and screwed into the wood, both side-pieces being arranged in a like manner.

What I claim is:

85

1. In a washboard of the character described, a frame consisting of two side-bars each having apertures therethrough at the lower end, a lower cross-bar and two upper cross-bars rigidly fixed to said side-bars, a 90 rubbing surface arranged in said frame, removable extension legs each provided with apertures therethrough, screw-bolts selectively passing through said apertures through said removable extension legs and 95 said side-bars, said screw-bolts having engaging washers and thumb-nuts and rigidly securing the removable extension legs to the ends of the frame.

2. In a washboard of the character described, a frame provided with grooves, and having apertures therethrough, metallic strips provided with apertures acting as bearings fixed in said grooves, grooved rollers, each having a metallic pin rigidly fixed 100 to one end, said rollers provided at the opposite end with a movable bearing pin having a flat head at one end, said pin loosely positioned by means of a sleeve through which said pin may extend so as to engage 105 a corresponding aperture in the bearing strip to allow a revolving movement of the roller, the flat head of said bearing pin engaging and acting upon a spiral spring 110 loosely fixed in a socket in the end of the 115 roller.

3. In a washboard of the character described, a frame consisting of two side-bars, a lower cross-bar and two upper cross-bars rigidly fixed to said side-bars, said upper 120 cross-bars being spaced from each other, a resting rail mounted above the top cross-bar by means of two sliding plates each having a longitudinal slot therethrough, screws provided with metallic washers passing through 125 the slots in said sliding plates and screwed into the side-bars, the upper end of each sliding plate being rigidly fastened to the corresponding end of said resting rail, the rail resting upon spiral springs positioned 130

between the rail and the top cross-bar of said frame, said spiral springs loosely held in sockets provided in the rail and the top cross-bar, the rail acting upon the spiral springs, and a rubbing face arranged in the frame.

In testimony whereof I have signed my

name to this specification in the presence of two subscribing witnesses.

GEORGE BERNARD WHEELER.
